UNITED STATES PATENT OFFICE.

NEWTON W. STERN, OF SAN FRANCISCO, CALIFORNIA.

DESIGN FOR A FLUSH-TANK COVER.

47,654.

Specification for Design.

Patented July 27, 1915.

Application filed April 5, 1915. Serial No. 19,378. Term of patent 7 years.

To all whom it may concern:

Be it known that I, NEWTON W. STERN, a citizen of the United States, residing in the city and county of San Francisco, State of California, have invented a new, original, and ornamental Design for Flush-Tank Covers, of which the following is a specification, reference being had to the accompanying drawing, forming part thereof.

The figure is a perspective view of a flush tank cover, showing my design.

I claim:

The ornamental design for a flush tank cover, substantially as shown.

NEWTON W. STERN.

Witness:

H. G. PROST.
